REGISTERING DEVICE FOR PRINTING

William L. McCarter, Hanford, Calif.

Application November 9, 1942, Serial No. 464,995

5 Claims. (Cl. 33—184.5)

My invention relates to the art of printing and has for its particular purpose the provision of devices by which imprinting may be produced simply and quickly and to secure exact registration. This invention has particular application where it is desired to imprint or to print successively copy in two colors.

My present invention relates generally to the same art as do my two co-pending applications for patent, one entitled Method for mounting and registering printing elements and the other Means for mounting and registering printing elements which applications are filed coincidently herewith, bearing Serial Nos. 464,997 and 464,996, respectively.

I attain the general objects of my invention by providing a flexible covering adapted to be removably secured to a printing cylinder. Said covering can be taken off and mounted about a cylindrical registering cylinder of substantially equal length and diameter embodying my invention. Said registering cylinder is adapted to revolve over a copy holding tray provided with toothed racks on the edges thereof. The registering cylinder has pinions at the ends adapted to mesh with the racks and a sheet of copy can be arranged upon said tray. The sheet of copy is identical in size to the eventual sheet to be printed or imprinted and in the spaces to be imprinted type elements, preferably of rubber, are arranged face down. Said type elements have adhesive on their backs. The surface of said tray is spaced from the under surface of said roller a distance substantially equal to the thickness of the type elements and thus when the registering cylinder is rotated over said copy, it picks up the type elements by adhesion and said type elements are thereby arranged upon the covering in proper position. Said covering can then be removed from the registering cylinder and placed upon the printing cylinder without further adjustment. By this means exact registration can be made, quickly and easily.

Other details of my invention are hereinafter described with reference to the accompanying drawing, in which:

Fig. 1 is a plan view looking down upon the copy holding tray with a sheet of copy shown thereon with type elements arranged in proper position, one corner of said copy paper being shown turned up;

Fig. 2 is an enlarged sectional view taken on the line 2—2 in Fig. 5 showing the relative arrangement of the registering cylinder, the covering thereon, the copy tray and type elements arranged thereon;

Fig. 3 is a sectional view taken on the line 3—3 in Fig. 1;

Fig. 4 is a foreshortened sectional view taken substantially on the line 4—4 in Fig. 5; and

Fig. 5 is a perspective view showing the registering cylinder in place on the copy holding tray with the pinions thereon in mesh with the racks at the side of said tray.

5 My invention is adapted to be used with a flexible covering 1 provided with eyelets 1a or other devices which permits it to be removably secured to a printing cylinder of any type of printing press (not shown). Said flexible covering is made of any flexible material and preferably but not necessarily may be made of a sheet of Celluloid or similar material which is adapted to lie flat upon the surface of the cylinder but which has sufficient flexibility so that recurring bending thereof will not rupture it. Said flexible covering may be detachably secured to an impression cylinder 2 embodying my invention. Such a cylinder has the same diameter and substantially the same length as the printing cylinder for which said covering is made. The cylinder is provided with two pinions 3, one at each end thereof, preferably with handles or guides 4 so that it can be rotated over a copy tray 5. The upper surface 6 of said copy tray is plane and extends over an area substantially equal to the surface area of the impression cylinder covering 1. Said tray is provided with racks 7 at the longitudinal edges thereof, which racks have teeth formed thereon adapted to mesh with the pinions 3 on the impression cylinder. Then if the cylinder is rolled lengthwise of the tray, it will be maintained in substantial alinement laterally of said tray. That is, the intermeshing of the teeth on the pinion with the teeth on the pairs of racks of the tray will not permit any differential rotation to take place between the ends of the impression cylinder. A sheet of copy 8 to be printed or imprinted, is arranged on the surface of said copy tray and type elements 9 are 20 arranged type down on said copy paper. Said type elements, preferably, are sheets of rubber or similar material and have adhesive 10, such, for example, as so-called "sticky-back" on their surfaces opposed to the type faces. Lying at the 25 edges of said tray are two ledges or rails 11 upon which the impression cylinder is supported. Said ledges are of a height substantially equal to the thickness of the type element. This is illustrated in Fig. 4. Thus, when the impression cylinder 30 with the covering arranged thereon is rotated over the type elements, the "sticky-back" of the type elements are adhesively secured to the flexible covering 1. It is not necessary to compress the type or to apply substantial pressure to secure this adhesion. A mere surface contact is 35 sufficient to produce this result. This permits type to be fastened to the covering without producing any misalinement and when the covering is removed from the impression cylinder and 40 placed upon a printing cylinder, the sheets to be

printed will have impressions made thereon by the type elements exactly in accordance with the arrangement of said type faces when they were originally placed upon the copy paper.

When the type has been arranged upon the copy paper, as is illustrated in Fig. 5, and the roller rotated lengthwise of the copy tray, the type is arranged upon the flexible covering in a matter of only a few seconds and a comparably short time is consumed in transferring the flexible covering from the impression cylinder to the printing cylinder.

It is not necessary that rack and pinion structures be provided but any type of notched inter-engagement of devices on the cylinder and on the copy holder will suffice which prevents axial movement of the impression cylinder or differential rotation of the ends thereof. Examples of devices of this character might be heavily milled or notched members or even a knurled surface on each end of said impression cylinder and upon the rails of the sides of the copy tray. I deem it preferable, however, to arrange these members as rack and pinion elements because they operate efficiently and differential movement is held within close limits to secure exact registration of the type elements upon the flexible covering.

I deem it important that the ledges or rails on the sides of the copy holding tray be of a height substantially equal to the thickness of the type elements and the thickness of the copy paper combined so that little or no distortion of the type elements is produced in transferring the letter to the flexible covering. It is to be understood that the thickness of the copy paper and that of the "sticky-back," if it is used, is more or less negligible and it might be said that the ledges or rails are spaced horizontally above the type positioning surfaces a distance substantially equal to the thickness of the type elements alone.

I claim.

1. In combination with a flexible removable covering adapted to be secured to a printing cylinder, a cylindrical registering member adapted removably to carry said covering about the periphery thereof and adapted to have type elements secured thereto, a copy holding tray presenting a plane type positioning surface of an area comparable to that of the area of said covering, longitudinal guides and a notched flange extending along one side of said base, said cylindrical member with the covering attached thereto being adapted to be rolled longitudinally over the type positioning surface of said base, a notched cylindrical member secured to one end of said cylindrical member and adapted for engagement with said notched member, whereby said cylindrical member is maintained in alinement and registration with said base when it is rolled over the latter.

2. In combination with a flexible removable covering adapted to be secured to a printing cylinder, a cylindrical registering member adapted removably to carry said covering about the periphery thereof and adapted to have type elements secured thereto, a copy holding tray presenting a plane type positioning surface of an area comparable to that of the area of said covering, said cylindrical member with the covering attached thereto being adapted to be rolled longitudinally over the type positioning surface of said base, a toothed rack formed along one side of said base, a pinion secured to one end of said cylindrical member and adapted for engagement

with said toothed rack, whereby said cylindrical member is maintained in alinement and registration with said base when it is rolled over the latter.

3. In combination with a flexible removable covering adapted to be secured to a printing cylinder, a cylindrical registering member adapted removably to carry said covering about the periphery thereof and adapted to have type elements secured thereto, a copy holding tray presenting a plane type positioning surface of an area comparable to that of the area of said covering, said cylindrical member with the covering attached thereto being adapted to be rolled longitudinally over the type positioning surface of said base, a toothed rack formed along the sides of said base, a pair of spaced pinions secured to the ends, respectively, of said cylindrical member and adapted for engagement with said toothed racks, whereby said cylindrical member is maintained in alinement and registration with said base when it is rolled over the latter.

4. In combination with a flexible removable covering adapted to be secured to a printing cylinder, a cylindrical registering member adapted removably to carry said covering about the periphery thereof and adapted to have type elements secured thereto, a copy holding tray presenting a plane type positioning surface of an area comparable to that of the area of said covering, longitudinal guides and a notched flange extending along one side of said base, said cylindrical member with the covering attached thereto being adapted to be rolled longitudinally over the type positioning surface of said base, a notched cylindrical member secured to one end of said cylindrical member and adapted for engagement with said notched member, whereby said cylindrical member is maintained in alinement and registration with said base when it is rolled over the latter, and type elements arranged upon said type positioning surface, said type elements having adhesive covered backs adapted to contact with and to be adhesively secured to said covering when said covered cylindrical registering member is rolled over said base.

5. In combination with a flexible removable covering adapted to be secured to a printing cylinder, a cylindrical registering member adapted removably to carry said covering about the periphery thereof and adapted to have type elements secured thereto, a copy holding tray presenting a plane type positioning surface of an area comparable to that of the area of said covering, longitudinal guides and a notched flange extending along one side of said base, said cylindrical member with the covering attached thereto being adapted to be rolled longitudinally over the type positioning surface of said base, a notched cylindrical member secured to one end of said cylindrical member and adapted for engagement with said notched member, whereby said cylindrical member is maintained in alinement and registration with said base when it is rolled over the latter, and type elements arranged upon said type positioning surface, said type elements having adhesive covered backs adapted to contact with and to be adhesively secured to said covering when said covered cylindrical registering member is rolled over said base, said guides being spaced above said type positioning surface a distance substantially equal to the thickness of said type elements.

WILLIAM L. McCARTER.
